No. 799,981.

PATENTED SEPT. 19, 1905.

C. A. FRYE.
METALLIC TIE.
APPLICATION FILED MAR. 27, 1905.

UNITED STATES PATENT OFFICE.

CHARLES A. FRYE, OF MONONGAHELA, PENNSYLVANIA.

METALLIC TIE.

No. 799,981.

Specification of Letters Patent.

Patented Sept. 19, 1905.

Application filed March 27, 1905. Serial No. 252,190.

To all whom it may concern:

Be it known that I, CHARLES A. FRYE, a citizen of the United States of America, residing at Monongahela, in the county of Washington and State of Pennsylvania, have invented certain new and useful Improvements in Metallic Ties, of which the following is a specification, reference being had therein to the accompanying drawings.

10 This invention relates to certain new and useful improvements in metallic ties and rail-fasteners; and the invention has for its object to provide a novel form of tie to which rails can be secured whereby they cannot spread 15 or become separated during the passage of rolling-stock over the same.

The invention aims to provide a metallic tie a portion of which has a corrugated or fluted lower face adapted to engage the ballast 20 of a road-bed and prevent the ties and rails from slipping or becoming displaced. The tie also serves as a cushioning-plate that will compensate for the jar caused by heavy loads passing over the rails or the jar occasioned 25 by the acceleration of the rolling-stock. The novel form of rail-fastener which I employ in connection with the tie also serves as a rail-joint that can be conveniently used in connection with the tie, and in the construction of 30 the rail-fastener and rail-joint allowance is made for the expansion and contraction of the rails due to the changes in temperature. Throughout the entire construction I have constructed the same upon simple lines, yet 35 maintain a strong, durable, and comparatively inexpensive article to manufacture.

With the above and other objects in view the invention finally consists in the novel construction, combination, and arrangement of 40 parts, which will be hereinafter more fully described and then specifically pointed out in the claims, and, referring to the drawings accompanying this application, like numerals of reference designate corresponding parts 45 throughout the several views, in which—

Figure 1 is a top plan view of my improved metallic tie, illustrating two rails secured thereon by my improved rail-fastener. Fig. 2 is a side elevation of the metallic tie as 50 illustrated in Fig. 1, partly in vertical section. Fig. 3 is a vertical sectional view taken on the line xx of Fig. 2. Fig. 4 is a vertical sectional view taken on the line yy of Fig. 2. Fig. 5 is a top plan view of my improved 55 metallic tie, illustrating a modified form of rail-fastener and rail-support. Fig. 6 is a

side elevation view of the same, partly in section. Fig. 7 is a side elevation view of a metallic tie constructed for use in connection with a third-rail system or for use in connection with switches where it is desired to support two or more rails, and in this view I have illustrated the modified form of rail fastener and support such as illustrated in Fig. 6. Fig. 8 is a vertical sectional view of 65 a modified form of rail-support.

In the accompanying drawings reference will first be had to Figs. 1 to 4, inclusive, wherein I have illustrated the preferred manner of constructing my improved metallic tie 70 and rail-fastener. The reference-numeral 1 designates the metallic tie in its entirety, and the tie is preferably formed of channel-iron and stamped or bent to provide countersunk portions or recesses 2 2 adjacent to each end 75 of the tie. The bottom surface of the tie 1 between the recesses 2 2 is cut away, as indicated at 3, to lighten the weight of the tie, also to provide means whereby the ballast of a road-bed will be facilitated in gripping and 80 engaging the under surface of the tie. To further aid the ballast in gripping the tie, I have provided the under surface of the ends of the tie with corrugated or fluted surfaces 4 4.

The tie upon each side of the recesses 2 2 is 85 provided with vertically-disposed apertures 5 5, and in these apertures are secured substantially T-shaped pins 6, employed for locking the rail-supports within the recesses 2 2. The rail-supports consist of a box-like structure 7, having tapering walls, and in each box is mounted a cushioning-plate, of wood or the like material, adapted to support and cushion the rails 8 8. The box-like structure 7 carries extending arms 9 9, each arm being cut 95 away, as indicated at 10, to lighten the construction of the rail-supports and at the same time provide means for engagement of tools when it is desired to shift or in any wise move the ties after the rails have been secured to 100 the same. The arms are provided with transverse flanges 11 11, and adjacent to each flange are provided apertures 12 12, through which passes my improved rail-fastener, which will be presently described. The arms have their 105 under faces cut away, as indicated at 14 14, to lighten the construction of the arms and are also provided with apertures 15 15, which are adapted to aline with the apertures 5 5 of the tie, whereby the pin 6 can be placed therein 110 to retain the arms 9 9 upon the tie. The T-shaped heads 16 of the pins 6 engage the

under faces of the tie and prevent the pins from passing upwardly through the tie. To secure the upper ends of the pins, I provide apertures 17, that are transversely arranged within the upper ends of the pins, and through these apertures keys 18 are passed, adapted to retain the arms 9 9 upon the tie.

Reference will now be had to the rail-fastening feature of my invention, and by referring to Fig. 2 of the drawings it will be seen that I employ fish-plates 19, the bases of which extend outwardly, as indicated at 20, and engage the transverse flanges 11 of the arms. Each fish-plate is provided with a depending lug 21, adapted to project through the apertures 12 of the arms 9 9. Each lug is provided with a transversely-disposed aperture 22, through which a key 23 is adapted to pass to retain the rail-fasteners in engagement with the arms 9 9. To prevent any lateral movement of the rail-fasteners upon the arms 9 9, I have provided the top surface of the arms adjacent to the apertures 12 with grooves 24 24, and in said grooves are adapted to engage the depending ribs 25 25 of the fish-plates 19.

In Figs. 5 and 6 of the drawings I have illustrated a slight modification in the construction of my improved device and more particularly the rail-fastening means. By referring to said figures it will be observed that I have dispensed with the fish-plates 19 and their appurtenant parts and have simply spiked the rails 8 8 to the wooden cushioning-blocks 26 26, the remainder of this construction being identical to that illustrated and described in connection with Figs. 1 to 4, inclusive, of the drawings.

In Fig. 7 of the drawings I have illustrated my improved metallic tie as being constructed applicable to third-rail systems or use in connection with switches where it is necessary that a third rail or guard-rail be maintained in connection with the main rails. In this construction I have provided the tie with an auxiliary or central recess 27, in which is mounted a rail-support similar to that heretofore described in connection with Figs. 1 to 4 of the drawings. It will be observed that the outwardly-extending arms 28 28 of the rail-support 29 are secured upon the sides of the recess 27 with the inwardly-extending arms 30 30 of the rail-supports 31 and 32, the pins 33 33 serving to secure the arms of the rail-supports to the tie.

In Fig. 8 of the drawings I have illustrated a modified form of rail-support adapted to be used when it is found essential to mount the securing-keys transversely of the rail-sections, this often being necessary where the longitudinal stresses and strains upon the rail-sections are considerable and may have a tendency to loosen the securing-keys if they were mounted parallel with the rail-sections, as illustrated in Fig. 2 of the drawings. The rail-support illustrated in Fig. 8 of the drawings comprises

a substantially inverted-U-shaped bridge or strap 34, the top of which is provided with apertures 35, adapted to receive vertically-disposed pins 36 36, which are employed for retaining a rail-section upon the support. The lower ends of these pins are provided with apertures, as indicated at 37 37, alining with apertures 38 38, formed in the sides of the rail-support, and through said apertures a transversely-disposed key 39 extends and is secured within the rail-support by a split key 40. The ends of the rail-support are bent outwardly, as indicated at 41, at right angles to the bridge or strap 34, and the under faces of the ends are fluted, as indicated at 42. When this rail-support is used in connection with my improved ties, the top surface of the tie upon which the rail-supports are adapted to rest is corrugated at 43 to engage the fluted surface of the rail-support and prevent any lateral movement of the support upon the ties. To insure a positive engagement of the rail-supports with the tie, I employ pins 44 and keys 45, similar to the pins 6 and the keys 18.

By referring to Figs. 2, 6, and 7 it will be observed that the box structures comprising the rail-supports are provided with a plurality of apertures 46 to allow for the expansion and contraction of the blocks retained within the rail-supports and also to reduce the weight of each support.

From the foregoing description taken in connection with the drawings it is apparent that I have designed a tie adapted to remain permanent in a road-bed without shifting after it has been once placed in position. The corrugated or fluted surface of the tie causes the tie to engage the ballast of a road-bed, and the construction of the same permits of easy and effective tamping to form a permanent foundation for the tie.

The manner in which I secure the rails to the tie dispenses with the use of nuts and bolts, consequently dispensing with the noise heretofore experienced in connection with the nuts and bolts becoming loose or detached. By employing a key and pin instead of bolts and nuts I have provided means whereby the wear on the rail-base can be taken up by the adjustment of the key or by inserting a small sheet-iron liner through the keyhole. It will be apparent to those skilled in the art of railway construction, that I have devised a novel form of tie and rail-fastener that will withstand the wear and tear to which railway-ties and their appurtenant parts are subjected, and while I have herein described the preferred manner of constructing the numerous parts of my invention it is obvious that various changes may be made in the details of construction without departing from the general spirit and scope of the invention.

What I claim, and desire to secure by Letters Patent, is—

1. The combination of a metallic tie having

a corrugated surface, said tie having recesses formed therein, rail-supports consisting of box-like structures, blocks mounted in said structures, outwardly-extending arms carried by said structures, fish-plates supported by said structures and adapted to engage rails mounted upon said blocks, depending lugs carried by said fish-plates, keys passing through said lugs, headed pins passing through said arms and said ties, and keys passing through said pins, substantially as described.

2. The combination of a metallic tie having a corrugated or fluted surface, said tie having recesses formed therein, adjacent to its ends, box-like structures mounted in said recesses and adapted to support rails, fish-plates mounted upon said box-like structures and adapted to embrace said rails, means for securing said box-like structures to said tie, and means for securing said fish-plates to said box-like structures, substantially as described.

3. The combination with a metallic tie having corrugated surfaces, of box structures mounted upon said tie, outwardly-extending arms carried by said structures, means to secure rails to said structures, and means to secure said outwardly-extending arms to said tie, substantially as described. 25

4. The combination of a metallic tie having a corrugated or fluted underneath surface, said tie having recesses formed therein adjacent to the ends of said tie, means to support rails within said recesses, and means to secure the first-named means to said tie, substantially as described. 30

In testimony whereof I affix my signature in the presence of two witnesses.

CHARLES A. FRYE.
